US00D825191S

(12) **United States Design Patent** (10) **Patent No.:** **US D825,191 S**
Schmid et al. (45) **Date of Patent:** **** Aug. 14, 2018**

(54) **TOOTHBRUSH**

(71) Applicant: **The Gillette Company LLC**, Boston, MA (US)

(72) Inventors: **Franziska Schmid**, Frankfurt am Main (DE); **Tilmann Winkler**, Kronberg (DE)

(73) Assignee: **The Procter & Gamble Company**, Cincinnati, OH (US)

(**) Term: **15 Years**

(21) Appl. No.: **29/556,176**

(22) Filed: **Feb. 29, 2016**

Related U.S. Application Data

(62) Division of application No. 29/501,810, filed on Sep. 9, 2014, now Pat. No. Des. 753,401.

(57) **CLAIM**

The ornamental design for a toothbrush, as shown and described above.

DESCRIPTION

FIG. 1 is a perspective view of a toothbrush showing our new design;

FIG. 2 is a front view thereof;

FIG. 3 is a right side view thereof;

FIG. 4 is a rear view thereof;

FIG. 5 is a left side view thereof;

FIG. 6 is a top plan view thereof; and,

FIG. 7 is a bottom view thereof.

The broken lines are shown for the purpose of illustrating parts of the toothbrush that form no part of the claimed design.

1 Claim, 2 Drawing Sheets
